HIGH FREQUENCY TUBE

Irving J. Saxl, New York, N. Y., assignor to Radio
Receptor Co. Inc., New York, N. Y., a corpora-
tion of New YorkApplication October 28, 1932, Serial No. 640,045
In Austria November 17, 1931

10 Claims. (Cl. 250—37.5)

This invention relates to high frequency generators and receivers, and is particularly directed to the provision of an oscillation generator of the vacuum type for generating oscillations of ultra short and quasi-optical wave length.

Wave lengths of the type aforementioned, can advantageously be employed for many purposes and in many arts, provided the same be produced of sufficient amplitude (that is with comparatively higher energy output than heretofore obtained with vacuum discharge tubes for generating waves of this type) and by simple and inexpensive means.

It is the object of this invention to provide a generator and receiver of the vacuum tube type whereby substantially higher energy output at ultra short and quasi-optical wave lengths may be produced in a highly efficient, simple and inexpensive manner.

Other objects of this invention will in part be obvious and in part hereinafter pointed out.

The invention consists in the method, features of construction, combinations of elements, and arrangement of parts which will be exemplified in the construction hereinafter described, and of which the scope of application will be indicated in the following claims.

A well-known method for producing very short waves is that of Barkhausen-Kurz in accordance with which the frequency is determined by the time during which the electrons remain in the space between the electrodes. In accordance with this method a pendular movement of the electrons relative to the grid is caused by imparting a high positive potential to the grid and a low negative or small positive potential to the anode, the electrons passing through the grid at high velocity being returned by the retarding field of the anode and thus made again to pass through the grid, and the pendular cycle thus then repeated. In this method, however, voltages of high frequency characteristics are generated upon the plate which tend to decrease the amplitude of the generated waves, i. e. the energy output. In accordance with this invention the capacity of the plate relative to ground is increased to such a degree that at the high frequencies aforementioned, the increased electric density over the plate reduces the variations of the voltages generated upon the same to such an extent that the plate voltage is practically stabilized. Thus the amplitudes of the high frequency voltages generated upon the grid are substantially greater than those generated over the plate, thus substantially increasing the amplitude of the generated waves. This increase of the plate capacity against ground should be accomplished without bringing in proximity to the tube any grounded conductor of electricity so as at the same time not to increase the capacity against

ground of the grid or other elements of the tube when increasing the plate capacity as above mentioned. Moreover, this increased capacity of the plate must be accomplished without in any way changing the electrical characteristics of the other interior elements of the tube.

I have found that the increase of plate capacity relative to ground in such way as to satisfy the aforementioned conditions, may preferably be accomplished in the manner and construction hereinafter described.

It is well known that the capacity of a cylinder increases as a positive function of its radius and length. Therefore, I obtain the desired effect in accordance with my invention by surrounding the plate cylinder with another cylinder of larger diameter, the diameter and length of the plate cylinder remaining unchanged. The inner and outer plate cylinders are spaced from each other and electrically connected with each other at several points by conducting pieces of length preferably equal to a small fraction of the wave length to be generated.

In the drawing accompanying this specification,

Fig. 1 is a vertical section of a vacuum tube embodying the invention;

Fig. 2 is a longitudinal cross-sectional view taken on line 2—2 of Fig. 1;

Fig. 3 is a cross-sectional view taken on line 3—3 of Fig. 1; and

Figs. 4 to 7 are diagrammatic views of the tube in which the connections to the various tube elements are differently arranged.

Referring now to Figs. 1 to 3, T is the vacuum tube in which are mounted the filament F, grid G and anode. The latter comprises an inner cylinder P surrounded by a concentric cylinder C of larger diameter, the two cylinders P and C being electrically connected by conducting pieces A¹, A², A³, A⁴. The filament F is supported at its ends by spring holders F¹, F² connected to lead wires F³, F⁴ carried out through the pressed portion S of the tube stem. The grid G is supported by the glass arm G¹, extending upwardly and formed from the tube stem, and a pair of holders G², G³ connected to the ends of the grid which is led out through the body of the tube by the leads G⁵, G⁶ electrically connected to the other end of said holders G², G³. The anode is supported by the brace member P¹, connected at its upper end to the outer cylinder C, the lower end passing into the stem through which the anode is led out by means of the lead wire P².

In Fig. 4 the inner cylinder anode as well as the filament and grid are arranged longitudinally in the tube, the filament being led out through each end of the tube by leads F⁵, F⁶, and the plate and grid being led out from the wall of the tube mid-way between the ends thereof respectively.

by means of the leads P^3 , P^4 , the latter being connected to the supporting member P^5 to which the ends of the grid are electrically connected.

In Fig. 5 a simplified construction is shown in which the anode voltage is led out through to top of the tube as at P^6 and the connection to the grid made through the pressed portion of the stem of the tube.

In Fig. 6 the grid and anode are led out through the top of the tube as at G^7 , P^7 and in Fig. 7 all the leads are carried through the pressed portion of the stem of the tube.

Increased energy output may be obtained by connecting tubes embodying this invention in parallel, for instance, according to the Lecher system, wherein the tubes are so connected that they cooperate properly and in correct phase.

In addition to the advantages of my construction above mentioned, it is to be noted that the larger cylinder serves to materially decrease the heating of the inner cylinder.

The supports or holders for the grid and anode need not be of metal throughout their length, but may be fused onto glass rods which are in turn fused at one end into the pressed portion of the stem, the opposite end serving to carry these tube elements.

While I have described my invention in relation to its embodiment in the form of an oscillation generator, I have found that vacuum tubes constructed in accordance with the invention may also be employed in the receiving end of a wireless system, and that such tubes are effective in connection with the reception of ultra short and quasi-optical waves; so that a generator tube in accordance with this invention may also be used in a given system as a receiver by proper switching arrangements.

While in the embodiment here shown, the increase of the anode capacity is accomplished by an additional cylinder of larger diameter, it will be understood that other methods may be resorted to for the purpose of obtaining such increased anode capacity, for example, instead of two concentric cylinders a single hollow cylinder of substantial wall thickness may be employed for the plate, and various other methods for increasing the plate capacity will readily occur to those skilled in the art.

It will thus be seen that there is provided a system and device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:—

1. A high frequency oscillation tube of the Barkhausen-Kurz type comprising a cathode, grid, anode and a metallic member disposed about said anode and electrically connected thereto and independent of said grid and cathode.

2. A high frequency oscillation tube of the Barkhausen-Kurz type comprising an envelope housing a filament, grid and anode, said anode to be energized during operation at a uniform potential lower than that of the grid, means for

increasing the amplitude of the generated wave comprising means for increasing the capacity against ground of the entire anode only.

3. A high frequency oscillation tube of the Barkhausen-Kurz type having an envelope housing a cathode, grid and anode, said anode adapted to be energized at a uniform potential lower than the grid and means for producing an anode capacity against ground independent of said cathode and grid sufficient to maintain the potential of the entire anode substantially constant during variations in grid potential.

4. A high frequency oscillation tube of the Barkhausen-Kurz type having an envelope housing a cathode, grid and anode, said anode adapted to be energized at a potential lower than that of the grid and means for producing an anode capacity against ground independent of said cathode and grid sufficient to inhibit the generation of high frequency voltage variations on the entire anode.

5. A tri-electrode vacuum discharge device of the short wave type comprising a filament, grid and anode, said anode adapted to be energized at a uniform potential during operation and comprising conductors spaced from each other in the direction of electron flow for the purpose of increasing the capacity against ground of said anode only.

6. A tri-electrode vacuum discharge device of the short wave type comprising a filament, grid and anode, said anode adapted to be energized at a uniform potential during operation and comprising conductors spaced from each other a fraction of the wave length to be generated and in the direction of electron flow for the purpose of increasing the capacity against ground of said anode only.

7. A high frequency oscillation tube of the Barkhausen-Kurz type comprising an envelope housing a cathode, grid and anode, said anode adapted to be energized at a uniform potential during operation and comprising conductors spaced from each other in the direction of electron flow and electrically conductively connected to each other for the purpose of increasing the capacity against ground of said anode only.

8. A high frequency oscillation tube of the Barkhausen-Kurz type comprising an envelope housing a cathode, grid and anode, said anode comprising a plurality of concentric cylindrical conductors spaced from each other in the direction of electron flow and electrically conductively connected to each other for the purpose of increasing the capacity against ground of said anode only.

9. A high frequency oscillation tube of the Barkhausen-Kurz type comprising an envelope housing a cathode, grid and anode, said anode to be energized during operation at a substantially uniform potential lower than the grid potential and having means to substantially inhibit the generation of high frequency voltage variations in all parts of said anode.

10. A high frequency oscillation tube of the Barkhausen-Kurz type comprising a cathode, grid and anode, and a conducting member disposed about said anode and intimately electrically connected thereto at a plurality of points and independent of said grid and cathode.

IRVING J. SAXL.

CERTIFICATE OF CORRECTION.

Patent No. 1,988,398.

January 15, 1935.

IRVING J. SAXL.

**It is hereby certified that error appears in the printed specification of the
the above numbered requiring correction as follows: Page 2, first column, line
5, for "to" read the; and that the said Letters Patent should be read with this
correction therein that the same may conform to the record of the case in the
Patent Office.**

Signed and sealed this 12th day of March, A. D. 1935.
